(57) **CLAIM**

The ornamental design for an external dosimeter patch, as shown and described.

DESCRIPTION

FIG. 1 is a front perspective view of an embodiment of an attached array of external dosimeter patches illustrating our design;

FIG. 2 is a front view thereof;

FIG. 3 is an end view thereof;

FIG. 4 is a rear view thereof;

FIG. 5 is an opposing end view thereof; and,

FIG. 6 is a side view thereof.

The broken lines shown herein are for illustrative purposes only and form no part of the claimed design. The illustrated device is not limited to the scale shown.
